UNITED STATES PATENT OFFICE

1,963,882

AUTOMATIC DOOR DRAFT STOP

Martin J. Brennan, Dunkirk, N. Y.

Application March 22, 1933, Serial No. 662,152

1 Claim. (Cl. 20—68)

The present invention relates to that general class of devices known as door weatherstrips, and relates more particularly to an automatically operable device for closing the open space between the bottom of the door and the floor or door sill and preventing the admission of cold air, dust, etc., past the door.

The invention has among its objects the production of a device of this nature which is simple, inexpensive, compact, attractive, durable, efficient and satisfactory for use wherever found applicable.

A furthermore particular object of the invention resides in the provision of a device of this nature which will be automatic in operation, that is, upon opening the door it will automatically adjust itself so as to clear the floor or sill and permit easy opening of the door and which, when the door is shut, will automatically seat on the floor or sill and closely fit the same.

With the above and numerous other objects in view as will appear as the description proceeds, the invention consists in certain novel features of construction, and in the combination and arrangement of parts as will be hereinafter more fully described and claimed.

In the drawings:

Figure 1 is a front elevation of the device embodying the features of my invention showing the same mounted on the lower portion of the door.

Figure 2 is a horizontal section taken substantially on the line 2—2 of Figure 1.

Figure 3 is a perspective view of a plate forming part of the device.

Figure 4 is a rear elevation of the device showing the same in what I term engaged position.

Figure 5 is a perspective view of one member of the device.

Figure 6 is a perspective view of the other member of the device.

Figure 7 is an elevation in detail showing the device in disengaged position.

Figure 8 is a section taken substantially on the line 9—9 of Figure 7 but showing the device in engaged position.

Figure 9 is a section taken substantially on the line 9—9 of Figure 7, and

Figure 10 is an enlarged detail perspective view of the weatherstripping device.

Referring to the drawings in detail it will be seen that the numeral 5 denotes a door, on the outer bottom surface of which is fixedly engaged a bar or strip 6 extending from the free edge

to the hinged edge. Numeral 7 denotes another strip mounted below the strip 6 and movable with respect to said strip 6. This strip 7 is connected to the strip 6 by means of a link 8 of elongated construction hingedly connected with 60 leaves 9 and 10 fixed respectively in opposite ends of recesses 11 and 12 of respective strips 6 and 7. A spring 14 is engaged with the strips 6 and 7 and tends to hold these strips in abutment with each other in the position shown in Figure 9 and 65 this spring is housed in recesses 17 and 18 formed in the front faces of strips 6 and 7 and adapted to notch together when the strips are in abutment.

A plate 19 is fixed by screws 20 or other suitable means to the strip 6 on the front face thereof and functions as a guide for the movable strip 7.

A roller 21 is mounted on a pin 22 projecting from the strip 7 adjacent the hinged edge of the 75 door and this roller is of such a diameter as to have a portion of its periphery slightly protrude beyond the end of the strip 7 so as to engage the door frame at the hinged edge of the door and when the door is closed this roller engages the 80 frame and causes the strip 7 to be moved longitudinally of the strip 6 and away therefrom and the pin 22 is accommodated by a slot 25 in the plate 19 and therefore the strip 7 is caused to be moved away from the strip 6 as the door is closed 85 thereby causing weather-stripping tube 28 to be engaged with the floor or sill of the doorway. This tube 28 is of flexible rubber like material or the like and is preferably mounted in place by a strip 29 and suitable fastening means 30. 90

It is thought that the construction, operation, utility and advantages of this invention will now be clearly understood by those skilled in this art without a more detailed description thereof.

The present embodiment of the invention has 95 been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its 105 advantages.

Having thus described my invention, what I claim as new is:

In combination with a door and its frame, a stationary strip connected with one face of the 110

door adjacent its lower edge, a movable strip located below the first strip, the upper edge of the movable strip and the lower edge of the stationary strip being flat and adapted to contact with each other when the movable strip is in raised position, said edges having elongated notches therein, each located adjacent an end of a strip, hinged plates fastened in opposite ends of said notches, an elongated hinged plate pivotally connected to the inner ends of said hinged plates, said edges of the two strips having elongated recesses therein opening out through the outer faces of the strips, said recesses being located adjacent the other ends of said strips, a spring having one end fastened in the inner end of the recess of the stationary strip and its other end

fastened in the outer end of the recess in the movable strip, whereby said spring will hold the two strips together, with the hinged end of the movable strip projecting from the adjacent end of the stationary strip, a plate having its upper part fastened to the outer face of the stationary strip, said plate depending from the stationary strip and forming a guide for the movable strip, and a roller carried by the projecting end of the movable strip for engaging a part of the frame for forcing said movable strip longitudinally and downwardly, and said plate having a downwardly and inwardly curved notch in one end thereof for receiving the axis of the roller when the movable strip is in lowered position. 90
